UNITED STATES PATENT OFFICE.

CHAUNCEY C. BALDWIN, OF PERTH AMBOY, NEW JERSEY, ASSIGNOR TO STANDARD UNDERGROUND CABLE COMPANY, OF PERTH AMBOY, NEW JERSEY, A CORPORATION OF PENNSYLVANIA.

ANNEALING FURNACE.

Application filed April 20, 1922. Serial No. 555,675.

To all whom it may concern:

Be it known that I, CHAUNCEY C. BALDWIN, a citizen of the United States, residing at Perth Amboy, county of Middlesex, and 5 State of New Jersey, have invented certain new and useful Improvements in Annealing Furnaces, fully described and represented in the following specification and the accompanying drawings, forming a part of the 10 same.

This invention relates to that class of annealing furnaces in which a retort is supported over a sealing, cooling or quenching-tank, and the charge of material to be annealed is lowered when annealed directly 15 downward from the retort into the water contained in said tank.

The retort is of inverted form and secured to a suitable base at or below the water level 20 in the tank; and the invention comprises an improved means of lifting the charge from the tank into the retort, for supporting the charge therein during the heating operation, and for lowering the charge into the tank to 25 be cooled, and finally lifting it from the water to a loading-floor where the material to be annealed is assembled in suitable form to be charged into the retort and afterward 30 returned to the said floor. The material is preferably assembled upon a platform or wagon which is transferred to a suitable carrier which sustains it in the different movements to which it is subjected.

The invention consists partly of fixtures 35 for connecting the sling of a crane to the carrier, and partly to the construction of the seat upon which the retort is sustained to permit the connections of the sling to engage the carrier upon both sides of the retort, and 40 to move the carrier without obstruction, from below the retort to the loading-floor.

Heretofore, the cooling-tank of such furnaces has been provided with various kinds of mechanism for handling the charge, to 45 place it in the retort and to quench it and return it to the loading-floor after it is annealed.

It is evident that mechanism operated 50 under water cannot so readily be kept in order, or repaired as readily as mechanism operated above the water level; and it is also evident that the less mechanism is employed to operate such an annealing furnace, the

less attention such mechanism requires and the less it is likely to get out of order. 55

In the present invention, mechanism located in the tank is wholly dispensed with, and also special mechanism such as has heretofore been employed; and the different movements of the charge are effected by an 60 overhead or travelling crane which, by means of a suitable "sling," is engaged with a carrier adapted to transfer the charge from the loading-floor to the retort, and back again when annealed. 65

The operating of the crane and its connections to the carrier will be understood by reference to the annexed drawing, in which Fig. 1 is a cross section of the retort and its combustion-chamber and the tank, with 70 the platform raised; Fig. 1^a is a plan of the carrier with the lifting-hooks and the loaded platform thereon; Fig. 1^b is an edge view of the carrier and platform without the connections to the crane; Fig. 2 is a longitudinal 75 section of a tank with the retort fixed over the tank at one end and a loading-floor arranged a little above the water level at the opposite end, the platform and coils resting upon the bottom of the tank; Fig. 3 is a plan of the tank with the loading-floor at one end and the base-plate for the retort at the opposite end, the lower half of such base-plate being omitted to show the supporting-beams; and Fig. 4 is a diagram showing the 80 relation of the locking-hook and links for coupling the carrier to the sling. Figs. 4 and 7 view the pillar at right-angles to the view in Figs. 5 and 6. 85

Figs. 5, 6 and 7 show the progressive movements of the locking-link into engagement with the locking-hook. 90

Fig. 5 shows the said link connected to one of the pillars for lifting the carrier; Fig. 6 shows the upper link engaged with a 95 stationary locking-hook; Fig. 7 shows the pillar moved downwardly a little to shift the load from the lower link to the upper link upon the locking-hook, the weight being thus carried by the second link, when the 100 lifting-hook is detached from the first.

Fig. 8 is a longitudinal section of the carrier and platform with a platform raising-truck inserted between the same, to remove the platform. 105

A collar 11 is shown upon the exterior of

the retort 12 near its open lower end, such collar resting upon a base-plate 13 which is supported on cantilever beams 14 so that the retort extends over the tank T, and projects into the water sufficiently to form a water-seal.

A combustion-chamber 15 is shown enclosing the body of the retort and would be heated by any suitable means as, for instance, 10 gas-burners applied to the inlets 16 in the usual manner. The gases are discharged from the smoke-chamber by a flue 17, but it is to be understood that the retort may be heated by any suitable means.

15 The end of the tank opposite the retort is provided with a loading-floor 18 separated from the retort by a sufficient space 37 to lift the carrier from the tank when immersed and transfer it to the said floor.

20 A trap-door 32 is shown hinged to the base-plate 13 and extends across the space to the loading-floor.

Such door forms a part of the floor when it is closed and affords safer access to the 25 different parts of the floor by such closing of the tank. The trap-door is, in practice, counterbalanced and is easily lifted, when required, by an air-hoist.

20 A carrier 19 is shown upon the floor with 30 a platform 20 thereon loaded with coils of wire 21.

The retort is charged by moving the carrier with the loaded platform beneath the retort and then raising these parts to the 35 point required to enclose the charge wholly within the retort above the water level. Such lifting of the carrier is effected by connecting it detachably to the chains of a sling as hereinafter set forth.

40 The carrier is proportioned or formed with extensions to project beyond the sides of the retort, as shown in Figs. 1 and 1^a, and pillars 23 are projected upwardly therefrom so that they extend above the water upon 45 opposite sides of the combustion-chamber 15, when the retort is charged.

The carrier is moved to shift the charge in the desired manner by an overhead traveling crane, which is shown in the usual form 50 with a movable bridge 22 running upon the side-frames 23, and provided with a carriage 24 movable upon the bridge.

The hoisting-chain or rope 25 which depends from the carriage 24 is connected to 55 a sling comprising a four-armed cross 34 with a chain 35 depending from each arm of the cross, which is proportioned to suspend the chains 35 in proximity to the pillars of the carrier when ready for engagement therewith.

These four chains are terminated each by a hook 10 to engage the pillars for lifting the carrier and locking it in its elevated position.

65 The pillars of the carrier are provided

each in the top with an eye 28, and upwardly projecting locking-hooks 29 are fixed rigidly to the furnace or its support, by which hooks the carrier and its load are suspended during the heat-treatment of the 70 charge.

A so-called "bottom-link" 26 is connected permanently with the eye of the pillar, and a so-called "upper-link" 27 is interlocked with the bottom link 26. The former is 75 provided to engage the hook 10 upon one of the chains 35 of the sling, which may then operate to lift the carrier and its load. The links 27 are provided to hook upon the locking-hooks 29, which can be effected by hand 80 when the crane has raised the pillars into proximity to the locking-hook, as shown in Fig. 6.

The locking-hooks 29 are fixed in such a position that when the platform is sufficiently raised the pillar-eyes stand in proximity to the locking-hooks, and the upper link 27 hangs loosely from the lower link during such movement. (see Fig. 5.) The upper link is therefore free to be 90 looped over the locking-hook 29, which forms a stationary and rigid support for the load in the retort, when the link 27 is engaged therewith.

The links 26 and 27 are made large 95 enough to admit both the lifting-hook 10 and the link 27 into the link 26, (see Fig. 7) so that the link 27 can be freely hooked over the locking-hook; and the hook 10 then disengaged from the link 27 and the crane 100 moved elsewhere. (See Fig. 7).

The weight of the load previously borne by the four pillar-links is transferred to the locking-hooks 29, by lowering the sling until the upper links bear fully upon the locking-hooks, as shown in Fig. 7.

The pillars are thus supported in the desired position, sustaining the charge in the retort during the entire period of annealing.

In the longitudinal movement of the carrier its pillars necessarily move in slots or spaces 31 in the floor over the tank, which spaces cut off the retort from the sides of the tank and necessitate its support upon the cantilever beams 14 or other means which extend parallel with the slots.

A particular connection of the platform and the carrier is shown in Figs. 2 and 8, by which the platform and its load may be 120 transferred from or to the carrier from or to any point in a factory, by using some type of platform-raising trucks which are now in common use and which are used in connection with a flat platform having depending edges which form legs 36 between which the platform-raising truck 38 can be inserted to raise the platform slightly from the carrier, which renders it movable by 125 the truck-handle.

Such trucks are operated electrically, mechanically or by hand.

The depending edges 36 upon the platform are shown in Fig. 2, and the carrier 19 is fitted thereto, so that when the platform is centrally beneath the retort the pillars upon the carrier are in line with the locking-hooks 29, to engage the same.

It will be observed that the use of a crane 10 and its sling to raise and lower the platform beneath the retort requires an overhung or cantilever support for the retort with slots 31 in the floor at opposite sides of the retort into which the pillars of the carrier may 18 move to bring the center of the platform beneath the center of the retort.

It is obviously immaterial how the chains of the sling are connected detachably to the carrier so as to move it up or down, or longitudinally in the tank. Any suitable means 20 may therefore be used for such detachable connection in the place of the permanent connection of the links to the pillars at their upper ends. Loose links may be used in 25 place of the links 27, which would operate precisely the same to lift the load and to hold the link 26 adjacent to the locking-hook as the construction shown in Figs. 5, 6 and 7, with only one disadvantage, that 30 loose links would not be permanently secured to any part of the mechanism and might therefore be mislaid or lost.

There is no mechanism required in this invention which can get out of order, or 35 which is exposed to the deteriorating effect of immersion in the tank. The retort is always water-sealed and is never opened to cause the cooling of its contents.

The cheapness of this apparatus is very 40 great compared to the cost of any special device applied to the tank for handling the platform and its load therein; as the crane requires only to be fitted with the proper sling, with means for engaging it to the 45 pillars upon the carrier, and the platform requires to be fitted with a suitable carrier, and the retort to be provided with suitable stationary locking-hooks upon which the 50 load of the charge can be suspended when it is elevated into the retort.

It will be observed that not a single piece of this mechanism is "finished," or requires 55 accuracy of form and size to make it operative, as the chains and hooks employed are all rough, and operate better, from the looseness of their fitting, than if they were highly finished and fitted accurately to one another.

If an electric crane be employed, automatic limit-switches can be connected thereto 60 for automatically controlling the height to which the charge is elevated within the retort, or lowered within the sealing-tank, the links being applied to the locking-hook to sustain the charge when at its highest position.

The hooks 29 are termed "locking-hooks" herein because they secure the retention of the charge in its adjusted position within the retort during the annealing operation.

It will be understood that the sole use of 70 the water in the tank is to fill the open bottom of the retort and prevent any access of air to the metal while being heated, as such access causes oxidation and discoloration.

It is therefore necessary that the water in 75 the tank should be maintained a little above the open mouth of the retort, to expose to the full heat of the retort all the articles which are carried by the platform, so it is necessary that the platform shall be moved 80 into the bottom of the retort a sufficient distance to bring all of such articles above the water-line.

It will be understood from the above description that the means for carrying out 85 my invention is not limited to the precise construction shown in the drawing.

The cantilever-beams 14 necessarily require suitable anchorage at their outer ends to balance the weight of the furnace and 90 its contents, and it will be understood that means for such purpose is in practice provided.

The platform which moves the load into the retort does not necessarily require a carrier detachable from the platform as it is only essential that extensions should project 95 from the platform beyond the outer wall of the furnace, from which extension connections may be made to the sling of the 100 crane.

Having thus set forth the nature of the invention what is claimed herein is:

1. An annealing furnace comprising a 105 tank with cantilever retort-seat at one end and a loading-floor at the other, the said seat having an inverted retort seated thereon with an aperture below the same for inserting the load in the retort, a platform fitted to enter the bottom of the retort with its load, and a traveling crane with connections for raising and lowering the platform below the retort and for depositing the platform with its load upon the loading-floor.

2. An annealing furnace having a suitably heated retort inverted over a sealing-tank, a movable platform supporting the load to be annealed within the retort, extensions connected with the platform and projected laterally beyond the sides of the retort, with pillars upon said extensions projecting above the tank and provided with means to engage a sling, and a crane for raising and lowering the sling to charge 120 and discharge the load into and out of the 125 retort.

3. An annealing furnace having a suitably heated retort inverted over a sealing-tank, a movable platform supporting the load to be annealed within the retort, extensions 130

- connected with the platform and projected laterally beyond the sides of the retort, pillars upon said extensions with an eye at the top of each, upwardly projecting locking-
5 hooks fixed to the retort, adjacent to the pillar-eyes, and two links for each of the pillars, one to engage the eye to lift the load and the other to engage the locking-
hooks to hang the load thereon.
- 10 4. An annealing furnace having a suitably heated retort fixed over a sealing-tank, a platform supporting the load to be annealed within the retort, a carrier applied to the lower side of the platform and extended
15 beyond the sides of the retort, and a crane and sling with means adapted to engage the opposite ends of the carrier for raising and lowering the loaded platform in the tank.
5. An annealing furnace constructed ac-
20 cording to claim 1, and having means for locking the carrier with the loaded platform in the retort.
6. An annealing furnace having a suitably heated retort fixed over a sealing-tank,
25 a platform supporting the load to be annealed within the retort and having downwardly projecting legs at its opposite edges, a carrier fitted to the lower ends of the legs with open space between the platform and
30 the carrier, in which space a hand-lift-truck may be inserted, and a crane and sling with means adapted to engage the opposite ends of the carrier.
7. An annealing furnace constructed ac-
35 cording to claim 3, and having means for locking the carrier with the loaded platform in the retort, and for disengaging the sling from the carrier when thus loaded.
8. An annealing furnace having a suit-
40 ably heated retort inverted over a sealing-
tank with cantilever-beams at one end to support the retort, a platform supporting the load to be annealed within the retort, a carrier applied to the lower side of the plat-
45 form and extended beyond the sides of the retort, and having upright pillars with means to engage a sling, and a travelling crane with sling engaged with the said
means for raising and lowering the carrier
50 below the retort, and means for locking the carrier in its elevated position.
9. An annealing furnace having a tank, a retort inverted over the tank, a floor over the tank around the retort, a platform to carry the charge into the retort, pillars connected with the platform and projected upwardly at opposite sides of the retort, a slot in the floor to clear the pillars at each side of the retort, and a travelling crane with a sling and means to engage the sling detach-
55 ably to the pillars, as herein set forth.
10. An annealing furnace constructed ac-
cording to claim 9, and having means connected with the retort for supporting the platform during the heating of the charge.
11. An annealing furnace having a seal-
60 ing-tank, cantilever projected over one end of the tank and provided with a base, a retort inverted over such base, a platform sup-
porting the load to be annealed within the
65 retort, extensions from the said platform to the sides of the cantilever base, slots at the sides of the furnace over the said extensions, and a crane having a sling adapted to move
70 in the slots with means to engage the ends of the said extensions.
12. An annealing furnace having a seal-
75 ing-tank, a retort inverted over the tank, a platform to carry the charge into the retort, pillars connected with the platform and pro-
80 jected upwardly at each side of the retort, and a travelling crane having a four-armed sling with chains fitted to engage the pillars
85 detachably.
13. The method of maneuvering the charge for an inverted stationary retort, which consists first in preparing the charge upon a loading-floor, second, lifting and suspending the same above the said floor and immersing it in the tank, third, mov-
90 ing the suspended charge through the water in the tank to a point beneath the retort, fourth, lifting the platform with its charge into the retort, and hanging it thereon, and fifth, lowering the charge from the retort
95 and moving it to the loading-floor and de-
positing it thereon with continuous suspen-
sion upon the lifting means throughout the entire operation.
- In testimony whereof I have hereunto set
my hand.
- CHAUNCEY C. BALDWIN.
